UNITED STATES PATENT OFFICE.

GEORGE K. MACK AND WILLIAM J. BERRYMAN, OF EDENTON, NORTH CAROLINA.

METAL DRAIN FOR ROADWAYS.

Application filed October 19, 1926. Serial No. 142,695.

This invention relates to drains, and more particularly to drains designed primarily for roadway surface drainage, but which may be used wherever there is occasion to 5 drain water from a soil surface to prevent washouts, and drainage due to the run-off of surface water.

It is designed especially for use on roadway embankments and through the berm or 10 ridge thereof, to prevent the excessive erosion so common in the case of surface water draining off embankments, causing costly and dangerous washouts.

The object of the present invention is to 15 provide an efficient and durable metal drain for a roadway, which drain is easily made and laid, and which permits ready removal or replacement in part or in whole if necessary.

20 Our invention is illustrated in the accompanying drawings, in which:—

Figure 1 represents a perspective view of the drain taken in the end thereof,

25 Figure 2 is a sectional view taken on line 2—2 of Figure 1, looking in the direction of the arrows,

Figure 3 is a plan view taken along the line 3—3 of Figure 1, and

30 Figure 4 is a section taken on the line 4—4 of Figure 2, and shows how the drain is installed.

Like parts are indicated by like reference characters throughout the drawings.

35 Referring to the drawings, it will be seen that the drain is composed of two sheets of metal, cut and bent to be fitted together as shown. The member 1, or so called "apron", is made by cutting the sheet from the top in two places, the length of the cut being 40 determined by the depth of the spout 3. The flap 2 of the apron is then bent 90° and riveted to the bottom of the spout, as shown in Figure 3. Three spout flaps 2' are bent and riveted to the apron as shown 45 in Figure 1.

The top and sides of the apron and spout are double flanged, as at 4, that is, the edges are bent at 90° twice, in practice, about one and one-half inches being required for 50 this flanging, which serves as a protection against sharp edges and for extra strength. The flanging of the apron and spout is done before the two are attached.

55 The drain is constructed of galvanized iron in flat sheets of sixteen gage, unless

otherwise specified. The metal is conformed to standard specifications for galvanized copper bearing metal, which may be modified to meet the cost of production or other conditions. The rivets are preferably one-quarter of an inch and galvanized. A reinforcing rod or strip, may be attached to the end of the spout, if necessary, for extra strength.

The width of the opening in the apron and spout is variable, being determined in practice by the amount of run off of water. The length of the spout is also variable in practice, it being equal to the height of the filled roadway.

As shown in Figure 4, the metal drain which has an open top, is inserted through the berm or ridge usual along the edge of each shoulder of the roadway embankment, the drain being on a slight incline, outwardly and downwardly, with the floor thereof coinciding or flush with the surface of roadway, the drain being anchored by the apron 1 which is embedded in the shoulder of the roadway, it being noted that the apron extends on both sides of the spout, holding it against slewling around from any cause.

On installations made on new construction jobs, it is advisable to build the berm of earth along the edge of each shoulder at the time the grading is done; this berm should be from eight to ten inches high and from one and a half to two feet in width at the bottom. Openings are then cut by hand at the low places in the grade requiring the drains, these openings being the width of the spout only; the drain is then placed in the opening so as to give a slope downwardly and is then pushed into the berm and pressure applied to the apron to anchor it in the shoulder of the roadway and driven down until the floor of the spout is down to grade.

This drain has proven very efficient in use and will, it is believed, practically solve the 100 problem of roadway maintenance, for when once properly installed requires no further attention for the life of the drain and being of metal and very strongly and rigidly made, the drain should last for many years, 105 thus saving annually the very great expense incident to the up-keep of the roadway.

Thus it will be seen that the present invention provides an efficient roadway surface drainage device, and one which the ini- 110

tial cost is comparatively slight and one which can be quickly and easily installed.

We claim:—

1. A roadway drain consisting of an open top trough adapted to extend through the berm of the roadway, the floor of the trough substantially co-inciding with the upper surface of the roadway, and anchor means for said trough, the anchor means comprising an apron depending from the front end of the spout and adapted to be embedded in the shoulder of the roadway.

2. A roadway drain as defined in claim 1,

the anchor means including an upstanding apron having a recess to receive the front end of the spout and wings at each side of the spout and below the spout adapted to be embedded in the shoulder of the roadway.

3. A roadway drain as defined in claim 1, the anchoring means including a depending apron and lateral wings at the front or entrance end of the spout.

GEORGE K. MACK.
WILLIAM J. BERRYMAN.
